Primary Examiner — Manpreet S Matharu*Assistant Examiner* — Keith J Wilson(74) *Attorney, Agent, or Firm* — Buchanan, Ingersoll & Rooney PC(57) **CLAIM**

The ornamental design for a deflector for a sprinkler head, as shown and described.

DESCRIPTION

FIG. 1 is a front elevational view of a deflector for a sprinkler head showing our new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof; and,

FIG. 7 is a perspective view thereof showing a front, bottom and left side.

The broken lines shown represents portions of a deflector for sprinkler head and form no part of the claimed design.

1 Claim, 7 Drawing Sheets(56)
